UNITED STATES PATENT OFFICE.

WILLIAM DUBILIER, OF NEW YORK, N. Y., ASSIGNOR TO DUBILIER CONDENSER AND RADIO CORPORATION, OF NEW YORK, N. Y., A CORPORATION OF DELAWARE.

DESIGN FOR AN ELECTRICAL CONDENSER.

Application filed December 28, 1923. Serial No. 8,175. Term of patent 14 years.

To all whom it may concern:

Be it known that I, WILLIAM DUBILIER, a citizen of the United States, residing at New York, in the county of New York and State of New York, have invented a new, original, and ornamental Design for Electrical Condensers, of which the following is a specification, reference being had to the accompanying drawing, forming part thereof.

Figure 1 is a front view of my new design; and

Figure 2 is a top view thereof.

I claim:

The ornamental design for an electrical condenser; as shown.

Signed at New York, in the county of New York and State of New York, this 26th day of December, 1923.

WILLIAM DUBILIER.
